UNITED STATES PATENT OFFICE.

TIMOTHY DRAKE, OF WINDSOR, CONNECTICUT.

IMPROVEMENT IN VAPOR-LAMPS.

Specification forming part of Letters Patent No. 37,811, dated March 3, 1863.

To all whom it may concern:

Be it known that I, TIMOTHY DRAKE, of Windsor, county of Hartford, and State of Connecticut, have invented a certain new and useful Improvement in Vapor-Lamps; and I do hereby declare that the same is described and represented in the following specification and drawings; and to enable others skilled in the art to make and use the same, I will proceed to describe its construction, referring to the drawings, in which the same letters indicate like parts in each of the figures.

The nature of this improvement in vapor-lamps consists in the combination or arrangement of an interior perforated-diaphragm vaporizing and gas chamber, to increase the rapidity and perfection of the generating process, and at the same time to secure a greater richness to its external appearance, and also to render it more convenient for adjustment of its parts.

In the accompanying drawings, Figures 1 and 2 are perpendicular sectional elevations of my improvement. Figs. 3 and 4 are perpendicular sectional elevations of the same in a modified form. Figs. 5 and 7 are horizontal sectional views cut through the line A. Figs. 6 and 8 are horizontal sectional views cut through the line B.

The tube is made in two parts, *a* *b*, and jointed at *c*.

d is the burner-tube, made whole, or it may be made in two parts, having one or more perforations, *e*, to allow the gas to flow into the chamber *f* and to the burner slit or perforations *g*.

h is a diaphragm fitted loosely inside of the upper portion of a tube, having a stem, *i*, fitted into the lower end of the burner tube *d*, and having perforations *j*, (more or less in number,) and a solid body of metal, *o*, extending down, which acts as a retort from the blaze to the fluid which surrounds it. Thus I separate the upper portion of the tube into two compartments, the upper one, *k*, as a gas-chamber and the lower one, *a'*, distillation-cham-

ber, which chamber I propose to fill around the solid metal *o*, to hold the diaphragm up to its place by means of suitable absorbing substance.

m are heater-plates made in the form of a half-circle, having conductors *n* extending downward and secured to a sliding tube, *p*, fitted loosely to the top end of the upper portion of the tube, so as to be easily adjusted to the flame. I propose sometimes to perforate the heater-plates *m*, and also sometimes to dispense with the plates *m*, using simply a rod or continuation of the conductors *n*, bent into such shape as to bring its sides parallel with and near to the blaze, instead of the heater-plates *m*.

The modifications shown in Figs. 3 and 4 are simply in dispensing with the tube *p* and fitting the conductors *n* to the openings *s* in the burner-tube *d* and diaphragm *h*, so that the heater *m* may be easily adjusted as may be desirable.

Fig. 9 simply indicates the mode of arranging this improvement to a bracket or hung lamp.

I believe that the benefit to the public to be derived from the use of my improvement is so clear and important that any further description is unnecessary, its operation, when ready for use, being much like those now in use.

What I claim, therefore, and desire to secure by Letters Patent, is, as a new improved article of manufacture, viz :

1. The combination of the heaters *m* *n*, chamber *k*, diaphragm *h*, and vaporizing-chamber *a*, substantially in the manner as and for the purpose described.

2. The heaters *m* *n*, with the interior perforated diaphragm, *h*, substantially in the manner and for the purpose described.

TIMOTHY DRAKE. [L. S.]
